ZIGZAG SEWING MACHINE

Arthur N. Hale, Stratford, Conn., assignor to The Singer Manufacturing Company, Elizabeth, N. J., a corporation of New Jersey

Application September 22, 1949, Serial No. 117,133

9 Claims. (Cl. 112—159)

1

This invention relates to sewing machines and more particularly to zigzag sewing machines of the lock-stitch type.

It has for its primary object to provide improved mechanism for shifting the lower stitch-forming devices transversely of the normal direction of feed in unison with the laterally vibrating upper stitch-forming devices, whereby zigzag stitches of exceptional length can be produced expeditiously and at high speed.

Another object of the present invention is to provide an improved form of loop-taker support by which a plurality of rotary loop-takers can be rigidly maintained in proper position during the lateral shifting thereof to accommodate the lateral throw of the needles in the formation of zigzag stitches.

Still another object of the invention is to provide a loop-taker support capable of being shifted laterally of the normal direction of feed of the work without disturbing the timing of the driving gears and without interrupting the driving relationship between the driven shaft in the loop-taker support and the driving shaft in the machine-bed.

Other features, objects and advantages of the present invention will appear from the detailed description of an illustrative form of the same, which will now be given in conjunction with the accompanying drawings, in which:

Fig. 1 is a front elevational view, partly in section, of a lock-stitch sewing machine embodying the present invention;

Fig. 2 is a bottom plan view, partly in section, showing the general arrangement of the components in the bed, together with the details of the shaft-coupling used;

Fig. 3 is an enlarged transverse vertical sectional view of the bed taken substantially along the line 3—3 of Fig. 2;

Fig. 4 is an enlarged transverse vertical sectional view of the bed taken substantially along the line 4—4, Fig. 2;

Fig. 5 is an enlarged top plan view of a portion of the machine-bed with the throat-plate and slide-plates removed to show the arrangement of the loop-takers relative to the feed-dog;

Fig. 6 is a transverse vertical sectional view taken substantially along the line 6—6, Fig. 5, illustrating the preferred way of supporting the hook-saddles;

Fig. 7 is a transverse vertical sectional view taken substantially along the line 7—7, Fig. 1, showing the adjustable eccentric used for vibrating the needle-bar frame laterally of the normal direction of feed;

2

Fig. 8 is a vertical sectional view of the lower portion of the detent used to lock the adjusting disk of the needle vibrating eccentric against turning when changing the width of the zigzag stitching, the detent being shown in adjusting disk locking position;

Fig. 9 is a bottom plan view of the detent shown in Fig. 8.

Referring now to the drawings, the illustrative machine comprises a frame having a base or work-support 10, a vertical standard 11, and an overhanging arm 12 terminating in a head 13. Power is supplied to the machine through a belt-driven pulley 14 from any suitable source of power, such as an electric transmitter. The pulley 14 is secured to a main drive shaft 15 which is journaled in suitable bearings provided within the arm 12. The main shaft 15, at the head end of the machine, has fast on it a counterbalanced crank 16 connected by the usual link 17 to an endwise reciprocatory needle-bar 18 carrying at its lower end one or more needles 19. The needle-bar 18 is mounted for endwise reciprocation in the spaced bearings 20 and 21 of a laterally vibratory needle-bar frame 22 fulcrumed at its upper end on a pivot-stud 23. At its lower end, the needle-bar frame 22 is slotted, as at 24, through which slot extends a stud 25 secured in the machine-head 13, the purpose of the stud 25 being to steady the needle-bar frame 22 during the lateral vibratory movement thereof about its pivot-stud 23.

The means for imparting the vibratory movement to the needle-bar frame 22 preferably comprises a pitman 26 connected at one end to the needle-bar frame and at its other end shaped in the form of a strap to embrace an adjustable eccentric 27 mounted on a rotary cross-shaft 28 journaled in the opposite side walls of the machine-arm 12. The cross-shaft 28 is driven from the arm-shaft 15, at one-half the speed of the arm-shaft, by the gears 29 and 30 (Figs. 1 and 7). The adjustable eccentric 27 may be of any well known type, but I prefer that it be similar to that forming the subject of the U. S. patent of W. Myers, No. 2,128,031, issued August 23, 1938. For the purposes of the present invention it will be sufficient to say that the adjustable eccentric is equipped with an adjusting disk 31 which, when held stationary while the arm-shaft 15 is manually turned, will effect a change in the eccentricity of the eccentric. To lock the adjusting disk 31 of the eccentric against turning, there is provided a spring-retracted detent 32 (Fig. 7) journaled in a shouldered bushing 33 fixed in the front side wall of the bracket-arm 12. When the

detent is depressed, its lower end is adapted to enter a notch 34 provided in the periphery of the adjusting disk 31 and thereby lock the same from turning with the remainder of the eccentric parts. To maintain the detent in depressed or adjusting disk locking position, the detent is preferably formed with a cross-bar 35 which is normally buried in a transverse slot 36 formed in the bottom of the bushing 33, but when the detent is depressed it is shifted out of the transverse slot, the 10 detent then being turned so that the cross-bar 35 abuts against the bottom of the bushing 33, as shown in Figs. 8 and 9. With the detent thus locked in depressed or eccentric adjusting position, the two hands of the operator are freed to 15 lock a loop-taker shifting eccentric later to be described and to turn the pulley 14 to effect simultaneous adjustment of the lateral throw of the needles and loop-takers.

In the production of relatively wide zigzag 20 stitching, it is necessary in the type of machine illustrated to shift the loop-takers laterally in unison with the laterally vibrating needles. In the present case a pair of loop-takers 37 and 38, which cooperate with the needles 19 in the production of lock-stitches, are carried by a suitable common support mounted for lateral reciprocation in the bed 10. As will be observed in Figs. 2 and 6, the loop-takers 37 and 38 are mounted on vertical shafts 39 and 40 which are journaled for rotation in antifriction bearings provided in suitable loop-taker saddles 41 and 42. The two saddles 41 and 42 are adapted to be firmly clamped in selected spaced relation by screws 43 and 44 on a tubular carrier 45 journaled for endwise reciprocation in lugs 46 and 47 preferably cast integral with the bed 10. At its inner end, the tubular carrier 45 has secured upon it, by screws 48, one end of a cross-arm 49 shaped at its other end to embrace the outer race 50 of a thrust ball-bearing 51 (Fig. 2). The outer race is secured in the cross-arm 49 between a shoulder 52 formed on the cross-arm and a retainer ring 53 secured by screws 54 to the face of the cross-arm. The inner race 55 of the ball-bearing is mounted on the outboard section 56 of a two-part rotary bed-shaft, which outboard section is journaled in bushings 57 and 58 fixed in lugs 59 and 60 depending from the bed 10. The inner race 55 of the ball-bearing is confined on the outboard shaft-section 56 between a thrust-collar 61 and the hub 62 of a spur-gear 63 which meshes with an internal gear 64 fixed on the inboard section 65 of the two-part rotary bed-shaft. The spur-gear 63 and the internal gear 64 comprise a coupling between the outboard and inboard sections of the bed-shaft by virtue of which coupling the outboard shaft-section 56 may be shifted endwise relative to the inboard shaft-section 65 in unison with the endwise movable hook-saddle carrier 45, without interrupting the driving relationship between the two shaft sections. The loop-takers 37 and 38, rotatably journaled in the two hook saddles 41 and 42, are driven through the gears 66, 67 and 68, 69 from the two-part bed-shaft which is connected by a belt 70 to the arm-shaft 15. It will be understood that the looper-taker saddles 41 and 42 are firmly clamped at their front ends on the carrier 45 and, as will be observed in Figs. 2 and 5, the rear end of each of the saddles is extended to form a projection 71, 72 disposed to rest upon the exposed ends of the elongated shaft-bearing bushings 57 and 58, the bushings serving as stationary abutments which cooperate with the saddle projections 71 and 72 in assisting the 75

clamps in retaining the saddles in their normal operative position.

From the foregoing, it will be understood that the tubular carrier 45 and the two loop-taker saddles 41 and 42 are shifted as a unit laterally of the line of seam formation and, that movable simultaneously with the carrier and saddles is the outboard shaft-section 56 of the two-part bed-shaft, the connection between the carrier 45 and the shaft-section 56 being effected by the cross-arm 49. The ball-bearing 51 carried by the cross-arm 49 provides for free rotation of the shaft-section 56 relative to the cross-arm, but functions primarily as a thrust bearing to displace the shaft-section 56 endwise in response to the side-wise movement of the cross-arm 49.

Means is provided for side-wise shifting the cross-arm 49, and this means is best shown in Figs. 2, 3 and 4. The cross-arm 49 is provided with an ear 73 apertured to receive a conical portion of a stud 74 threaded into the split end of a link 75 connected at its other end by a conical bodied stud 76 to one arm 77^a of a bell-crank lever 77. To bind the studs 74 and 76 against accidental unthreading in the split ends of the link 75, there are provided the draw-screws 78 and 79 which, when tightened, tend to pull the split ends of the link together in a manner to frictionally lock the studs 74 and 76 against turning. As shown in Fig. 3, the body portion of the bell-crank lever 77 is forked to straddle the inboard section 65 of the bed-shaft and provide upper and lower bearings into which extend alined pivot-pins 80 and 81 fixed in the vertically spaced lugs 82 and 83 of a supporting bracket 84 attached to the machine-bed 10 preferably by screws 85. The other arm 77^b of the bell-crank lever 77 is preferably formed cylindrical and slidingly enters a hole bored transversely of a bearing pin 86 freely journaled in a socket 87 formed in one end-portion of a pitman 88 embracing at its other end a loop-taker shifting adjustable eccentric 89 similar in construction to eccentric 27. At its end remote from the eccentric 89, the pitman 88 is provided with spaced fingers 90 which slidingly engage the flattened sides of a guide-pin 91 secured in the supporting bracket 84, whereby the pitman 88 is steadied during its actuation by the eccentric 89. The eccentric 89 is mounted on a countershaft 92 which derives its rotary motion through a belt 93 from the arm-shaft 15, the speed of the countershaft being one-half that of the arm-shaft. From the above description, it will be appreciated that rotation of the arm-shaft 15 will impart a rotary motion to the eccentric 89, which in turn will actuate the pitman 88, the endwise components of the pitman movement being utilized to oscillate the bell-crank lever 77 about its pivot-pins 81 and 82. Oscillation of the bell-crank lever 77 will impart endwise movements to the link 75 and thus shift the cross-arm 49 sidewise. As previously explained, the detent 32 is used for assisting in adjusting the eccentricity of the needle-vibrating eccentric 27. As shown in Fig. 1, there is provided a spring-retracted detent 94 which can be manually depressed to enter and lock against turning an adjusting disk 95 of the loop-taker shifting eccentric 89. When both of the detents 32 and 94 are in depressed position the adjusting disks of the eccentrics 27 and 89 are locked and a manual turning of the pulley 14 will effect a simultaneous adjustment of the eccentricities of the eccentrics.

In effecting the production of zigzag stitch-

ing, it is necessary that the work be advanced past the stitch-forming instrumentalities in proper coordination with the lateral vibration of said instrumentalities. In the machine chosen to illustrate the invention, the work is advanced by a conventional four-motion feeding mechanism. This mechanism, best shown in Fig. 2, is actuated from the two-part bed-shaft 56, 65 and comprises a feed-advance adjustable eccentric 96 embraced by one end of a pitman 97 connected at its other end to the lower end of a depending rock-arm 98 which is clamped on a feed-advance rock-shaft 99 journaled in bearing bushings 100, 101 fixed in the bed 10. Clamped upon the rock-shaft 99 is an upstanding feed-rocker 102 having pivoted to its upper extremity a feed-bar 103 forked at its rear end to straddle and engage a feed-lift eccentric 104 mounted on the outboard section 56 of the rotary bed-shaft. Carried by the feed-bar 103 is a common form of feed-dog 105 (Figs. 1 and 5), the teeth of which are adapted to project through the feed-dog slots in a throat-plate 106 mounted on the bed 10. Opposing the feed-dog 105 is a presser-foot fastened to the lower end of a spring-depressed presser-bar 108. It will be understood that the four-motion feeding mechanism will not be shifted transversely of the seam line in unison with the lower stitch-forming devices. Since, however, the outboard shaft-section 56 does move laterally as part of the lower stitch-forming unit, the feed-lift eccentric 104 is made long so that it can shift endwise with the shaft-section 56 without becoming disengaged from the forked end of the feed-bar 103.

In the operation of the machine, the needles will be reciprocated once for each rotation of the arm-shaft 15 and also they will be vibrated transversely of the line of feed in the manner described to impart a lateral throw to the needles which, when coordinated with the four-motion feed, results in the formation of zigzag stitches. At the same time, through the belt connections 93 with the arm-shaft 15, the countershaft 92 is rotated and through the eccentric 89, pitman 88, bell-crank 77 and link 75 drives the loop-taker saddle carrier 45 and the outboard shaft-section 56 of the bed-shaft, together with all the connected elements, in unison with the vibrating needles. It will be appreciated that the cross-arm connection 49 between the carrier 45 and the outboard shaft-section 56 effectively ties these elements together so that they move as a single unit or assembly in response to the rotation of the actuating eccentric 89. The mechanism for shifting this assembly is compactly arranged in the sewing machine bed in a manner such that the components thereof can be sturdily mounted while being readily accessible for assembly and repair. It will be seen in Figs. 2 and 6 that the loop-taker supporting shafts 39 and 40 are journaled in vertically arranged antifriction bearings provided in the saddles 41 and 42, and that the shafts 39 and 40 are located intermediate the carrier 45 and the outboard shaft section 56. The location of the loop-taker supporting shafts 39 and 40 between the carrier 45 and the outboard shaft section 56 is advantageous from the viewpoint that it reduces by approximately half the small amount of turning movement of the carrier 45 about its longitudinal axis resulting from the play in the ball-bearing 51. The intermediate position of the loop-taker supporting shafts therefore contributes to the rigidity of the lower stitch-forming mechanism.

Having thus set forth the nature of the invention, what I claim herein is:

1. In a sewing machine having a frame including a bed and an overhanging bracket-arm, a rotary arm-shaft journaled in said bracket-arm, an endwise reciprocatory and laterally vibratory needle carried by said bracket arm, a second shaft journaled in said bracket-arm and actuated by and disposed transversely of said arm-shaft, an adjustable eccentric mounted on said second shaft, connections actuated by said eccentric for vibrating said needle, a bed-shaft journaled in said bed, a movable loop-taker mounted for lateral vibration in said bed, operative connections with said bed-shaft for imparting needle-thread loop-seizing movements to said loop-taker, a counter-shaft having a longitudinal axis disposed substantially parallel to the longitudinal axis of said bed-shaft, an adjustable eccentric mounted on said countershaft, means for actuating said countershaft, and connections actuated by said eccentric for vibrating said loop-taker in timed relation with said laterally vibrating needle.
2. In a sewing machine having a frame including a bed and an overhanging bracket-arm, an endwise reciprocatory and laterally vibratory needle supported by said bracket-arm, a two-part shaft journaled in said bed and having inboard and outboard sections coupled together for limited relative endwise movement, a carrier slidably supported in said bed, a loop-taker mounted on said carrier and operatively connected to the outboard section of said two-part shaft, a cross-arm connection between said carrier and said outboard shaft-section forming with said carrier and said shaft-section a unitary assembly, a rotary shaft, an eccentric mounted on said rotary shaft, and a link pivoted at one end to said cross-arm and at its other end operatively connected to said eccentric whereby when said shaft is rotated said unitary assembly is vibrated in unison with said laterally vibrating needle.
3. In a sewing machine having a frame including a bed and an overhanging bracket-arm, an endwise reciprocatory and laterally vibratory needle supported by said bracket-arm, a two-part shaft journaled in said bed and having inboard and outboard sections coupled together for limited relative endwise movement, a carrier slidably supported in said bed, a loop-taker mounted on said carrier and operatively connected to the outboard section of said two-part shaft, a cross-arm connection between said carrier and said outboard shaft-section forming with said carrier and said shaft-section a unitary assembly, a rotary shaft, an eccentric mounted on said rotary shaft, a link pivoted at one end to said cross-arm, a bell-crank lever pivotally supported on said bed and having one of its arms connected to said link, and a pitman connecting the other arm of said bell-crank lever to said eccentric.
4. In a sewing machine having a frame including a bed and an overhanging bracket-arm, an endwise reciprocatory and laterally vibratory needle supported by said bracket-arm, a two-part shaft journaled in said bed and having inboard and outboard sections coupled together for limited relative endwise movement, a carrier slidably supported in said bed in substantial parallelism with the outboard section of said two-part shaft, a loop-taker mounted on said carrier and operatively driven by said outboard shaft-section, a cross-member clamped on said carrier and having said outboard shaft-section rotat-

ably journaled therein but constrained against endwise movement thereto, a rotary shaft, and connections between said rotary shaft and said cross-member for moving said loop-taker laterally in unison with said laterally vibrating needle.

5. In a sewing machine having a frame including a bed and an overhanging bracket-arm, an endwise reciprocatory and laterally vibratory needle supported by said bracket-arm, a two-part shaft journaled in said bed and having inboard and outboard sections coupled together for limited relative endwise movement, a carrier slidably supported in said bed in substantial parallelism with the outboard section of said two-part shaft, a loop-taker mounted on said carrier and operatively driven by said outboard shaft-section, a cross-arm fixed on said carrier and carrying a ball-bearing in which is rotatably journaled said outboard shaft-section, means constraining said outboard shaft-section against endwise movement relative to said cross-arm, a rotary shaft journaled in said bed, and connections between said rotary shaft and said cross-member for moving said loop-taker laterally in unison with said laterally vibrating needle.

6. In a sewing machine having a frame including a bed and an overhanging bracket-arm, an endwise reciprocatory and laterally vibratory needle carried by said bracket-arm, a two-part shaft journaled in said bed and having aligned inboard and outboard sections coupled together for limited relative endwise movement, a carrier slidably supported in said bed for movement in a direction parallel to the longitudinal axis of said two-part shaft, a loop-taker mounted on said carrier, gearing operatively connecting said loop-taker to said outboard shaft-section, a cross-arm rigid with said carrier and carrying a bearing in which said outboard shaft-section is rotatably journaled, means for causing said outboard shaft-section to shift with said cross-arm, a rotary shaft journaled in said bed, a link connected at one end to said cross-arm, a bell-crank lever pivotally supported on said bed and having one of its arms connected to the other end of said link, an eccentric on said rotary shaft, and a pitman connecting the other arm of said bell-crank lever to said eccentric.

7. In a sewing machine having a frame including a bed and an overhanging bracket-arm, an endwise reciprocatory and laterally vibratory needle supported by said bracket-arm, a two-part shaft journaled in said bed and having inboard and outboard sections coupled together for limited relative endwise movement, a carrier 50 slidably supported in said bed in spaced relation relative to said two-part shaft, a loop-taker,

5. a loop-taker supporting shaft journaled in said carrier intermediate said carrier and two-part shaft, a cross-arm connection between said carrier and said outboard shaft section, and mechanism connected to said cross-arm and actuated to vibrate said loop-taker laterally in unison with the laterally vibrating needle.

8. In a sewing machine having a frame including a bed and an overhanging bracket-arm, an endwise reciprocatory and laterally vibratory needle supported by said bracket-arm, a two-part shaft journaled in said bed and having inboard and outboard sections coupled together for limited relative endwise movement, a carrier 10 slidably supported in said bed in spaced relation relative to said two-part shaft, a loop-taker, a loop-taker supporting shaft journaled in said carrier intermediate said carrier and two-part shaft, said loop-taker supporting shaft disposed so that its axis intersects the plane containing the longitudinal axes of said carrier and said outboard shaft section, a cross-arm connection between said carrier and said outboard shaft section, and mechanism connected to said cross-arm and actuated to vibrate said loop-taker laterally in unison with the laterally vibrating needle.

9. In a sewing machine having a frame including a bed and an overhanging bracket-arm, an endwise reciprocatory and laterally vibratory needle supported by said bracket-arm, a two-part shaft journaled horizontally in said bed and having inboard and outboard sections coupled together for limited relative endwise movement, a carrier disposed in spaced relation relative to said two-part shaft and slidably supported in said bed for movement parallel to the longitudinal axis of said two-part shaft, a loop-taker, a loop-taker supporting shaft journaled in vertically disposed bearings provided in said carrier, a cross-arm connection between said carrier and outboard shaft section forming with said carrier and said shaft section a unitary assembly, and connections actuated to vibrate said assembly laterally in unison with the laterally vibrating needle.

ARTHUR N. HALE.
